24 Claims. (Cl. 66—82)

This invention comprises improvements in or relating to knitting machines and in the production of fabric thereon. More particularly the invention refers to straight bar knitting machines, and an important object of the invention is to provide an improved and simplified mode of and means for knitting on this class of machine fabric embodying locked or tied stitches which give to the fabric non-ladder or ladder-resisting properties. Preferably the type of fabric it is intended to produce is that wherein stitch loops are locked or tied by loops other than stitch loops, a particular type of such fabric being that wherein in each locked stitch is composed of a loop of locking thread passing through and also around the stitch loop to be locked.

One convenient method of making a locked or tied stitch is by the employment of a spring or bearded needle having the tail end of its beard turned back towards the shank to form a comparatively small subsidiary hook; and the present invention is particularly, but not exclusively, concerned with a straight bar knitting machine embodying spring or bearded needles as above, thread feeding means, means for operating said needles to receive thread and produce therefrom ordinary stitch loops and means functioning subsequently to operate the needles to receive stitch-locking thread, form loops therefrom and pass said loops through and around the said stitch loops to lock or tie same.

In making a locked stitch on a needle of the kind above-described, a previously formed stitch loop to be locked is first cleared on the needle shank, after which stitch-locking thread is fed into the beard, and the needle is retracted to carry the locking thread to the top or bend of the beard and also to carry the old loop into the beard above the subsidiary hook at the tail of the beard. On subsequent projection of the needle the old loop is caught by the subsidiary hook and continued projection pulls the old loop down in said subsidiary hook and clears the locking thread loop below the beard, after which, by retraction of the needle, the locking loop is drawn through the old loop and cast off around said old loop which is still retained on the needle.

During the making of a locked stitch as above it is essential that the locking thread loop and the stitch loop to be locked thereby are so controlled as to ensure that the locking loop is maintained clear of the stitch loop at the time the latter is engaged by the subsidiary hook of the beard, and also to ensure that when the locking thread loop is drawn through the old loop

and passed on to the exterior of the beard prior to knocking over, the already formed fabric is definitely held down so as not to foul the stitch-locking loop and so as to hold the old loop in the requisite position for permitting the passage therethrough of the locking loop. In its broadest aspect the present invention resides in a knitting machine for producing fabric in which a loop of a locking thread is passed through and also around a previously formed stitch loop, the combination with loop-forming knitting needles, thread-feeding means therefor and means to operate said needles to receive thread from the said feeder and produce therefrom ordinary stitch loops, of other means functioning subsequently to the production of the ordinary stitch loops and operating to receive a locking thread and form loops therefrom and pass said loops through and around said stitch loops to lock them, and means for restricting movement of the stitch loops on the knitting needles in either direction lengthwise of said needles so that locking loops can be passed through said stitch loops.

As will be appreciated from the foregoing discussion of the production of the particular variety of ladder-resistant fabric with which this invention is concerned, the fabric is, as before-stated, desirably produced by the employment of a needle having the end of its hook turned back to form a subsidiary hook, which needle is moved longitudinally to engage a previously formed stitch loop in said subsidiary hook and lift it over a locking loop; and according to a feature of the invention the production of the fabric on such a needle is characterized by the step of holding the fabric down during operation, desirably at the plain side of the needle.

The invention also includes an improved construction of sinker functioning to maintain positive control of a stitch-locking loop and the disposition of same on the needle from the time of forming said loop to the time that it is passed over on to the exterior of the beard for casting off. Additionally the improved sinker is so constructed as to ensure that no undue strain is exerted on the stitch loop to be locked or upon the locking thread loop during the formation of a locked stitch. To this end the improved sinker is provided with an additional thread-accommodating throat at the forward end of the sinker for receiving the locking thread loop and controlling the disposition of same on the needle during stitch formation, and said additional forward throat advantageously has its closed end level or approximately level with the underface or edge

of that part of the sinker immediately at the rear of said throat, this being preferably accomplished by cutting away or recessing the sinker on its underside immediately at the rear of the forward throat.

5 The specially constructed sinkers with additional forward throats advantageously constitute dividing sinkers alternating with jack sinkers along the machine, which jack sinkers are operated in the well known manner to sink thread between alternate pairs of needles after thread laying, while the dividing sinkers are subsequently projected between the remaining alternate pairs of needles to divide the thread loops sunk by the jack sinkers, and during the production of locked stitches the dividing sinkers are operated after the sinking and dividing of locking thread loops to receive said locking thread loops in their forward throats and maintain control of said locking thread loops throughout the operation of producing locked stitches, or the major part of said operation.

The invention also includes differently designed cams for controlling the stitch-producing mechanism for making either plain or ordinary stitches and locked or tied stitches at will together with means for automatically transferring the operation from ordinary or plain stitch production to the locked stitch production at predetermined intervals, e. g., on alternate stitch courses. Additionally means are provided for effecting independent adjustment of the size or quality of the stitch loops and the stitch-locking loops at will, thereby enabling a comparatively tight stitch loop with a comparatively slack locking loop to be produced or vice versa, the adjustment being automatically controlled.

For the purpose of more fully describing the nature of this invention reference will now be made to the accompanying drawings, wherein:

40 Figs. 1 to 8 illustrate eight successive steps in the production of a locked or tied knitted stitch on a straight bar knitting machine.

Fig. 9 is a perspective view showing the relative positions of the needles and sinkers at that phase in the production of fabric illustrated in Fig. 6.

Fig. 10 is a front elevational view of a single head straight bar machine embodying means in accordance with this invention for producing fabric with locked or tied stitches.

Fig. 11 is an enlarged sectional end elevation through part of the machine shown in Fig. 10.

Fig. 12 is an enlarged front elevation of part 55 of the mechanism on the machine shown in Fig. 10.

Fig. 20 shows the catch bar cams.

Fig. 21 is an enlarged end elevational view of mechanism shown at the right hand side of 75 Fig. 10 for making the fabric selvedge.

Fig. 22 is an enlarged plan of the upper part of Fig. 21.

Fig. 23 is a detail showing a yarn carrier driver and stop device therefor looking from the front of the machine.

Fig. 24 is a face view of the racking cams and bluff cams functioning at the fabric selvedges.

Fig. 25 shows the rack cams and bluff cam operating when selvedging the parallel fabric.

Fig. 26 shows the rack cam and bluff cam operating when fashioning.

Fig. 27 shows a jack sinker.

Fig. 28 shows a divider sinker, and

Fig. 29 shows a divider sinker employed at the selvedge.

In a convenient method of carrying out the invention on a straight bar knitting machine, needles 1 as before-mentioned are employed having beards 2 each terminating in a small inwardly turned subsidiary hook 3. Co-operating with 20 and working between alternate pairs of adjacent needles are jack sinkers 4 each having an angular loop-sinking throat 5 functioning to receive and control fed thread, while between the remaining alternate pairs of needles divider sinkers 6 operate, the jack sinkers 4 being first projected to sink thread loops between alternate pairs of needles and the dividers 6 being subsequently projected simultaneously with the outward movement of the needles to divide the 30 thread loops in the angular throats 7 in the known manner. Each divider 6 is preferably formed with a downwardly inclined portion 8 at that part immediately above the throat 1, and extending forwardly below said throat 1 is a portion 9 having a downwardly inclined upper edge, said portion 9 being provided with a comparatively narrow and preferably parallel sided throat 10 substantially near to the bottom edge of the sinker, and a substantially narrow and preferably parallel edged neb 11 projecting forwardly beyond and below said throat 10, said neb advantageously having horizontal upper and lower edges or faces.

The production of a locked or tied stitch by the co-operation of the aforesaid needles 1 and sinkers 4 and 6 will now be described, and for the sake of clearness the operation of a single needle will be described with reference to Figs. 1 to 8. First let it be assumed that a stitch loop *a* which it is required to lock is already carried on the needle, the needle is raised to clear said old loop down its shank, the sinkers are retracted to a position for permitting locking thread to be fed across the needle below the beard, the jack sinkers 4 are projected while the divider sinkers 6 are held back, (Fig. 1), after which, as the needle begins to descend and also to move outwards, the divider sinkers 6 are projected so as to sink a loop *b* of locking thread on the shank in the throats 5 and 7. Continued retraction of the needle brings the sunk loop *b* of locking thread into the top or bight *2a* of the needle beard 2 and also brings the old loop *a* up into the beard. During this motion the sinkers 4, 6 are simultaneously partially retracted, thereby causing the loop of locking thread to move out of the throats 5 and 7 off the jack sinker 4 and on to the small forward neb 11 of the divider sinker 6 (Fig. 3). The sinkers 4, 6 are now again projected a short distance to draw the locking thread into the back of the throat 10 of sinker 6 and below the neb of the adjacent jack sinker 4 to the position shown in Fig. 4. At this position a bar 12

on the plain side of the needles is moved towards the needle immediately below the forwardly projecting sinker neb 11 and above the fabric extending from the needle, and the needle is simultaneously moved into engagement with a presser bar 13 to press the beard 2, and while so pressed the needle commences to rise so as to bring the old loop *a* into the subsidiary hook 3, (Fig. 5). The bar 12 during this upward movement of the needles holds the fabric down and prevents the old loop *a* from creeping up against the locking thread loop *b*, consequently causing said old loop *a* to enter the subsidiary hook 3 while maintaining the locking thread loop clear of same. Pressure is now released from the beard and, as the aforesaid holding down bar 12 commences to move back, the needle is raised further to clear the loop of locking thread *b* below the beard 2, the old loop *a* being still held down in the subsidiary hook (Fig. 6). Pressure is now again applied to the needle beard and the needle is moved down so as to cause the locking loop *b* to be drawn through the old loop *a* and pass on to the exterior of the beard, (Fig. 7), the old loop meanwhile moving out of the subsidiary hook 3. During further retraction of the needle the sinkers are withdrawn and the locking loop *b*, which as aforesaid has been drawn through the old loop *a*, is thereby released from the sinker 6 and cast off over said old loop which is retained on the needle. If desired, the customary knocking-over bits 14 may, just prior to the projection of the holding down bar 12, be slightly lowered to assist in the movement of said bar up to the needles, said knocking over bits being subsequently raised at the time of knocking over and, if desired, moved in the direction of the arrow in Fig. 8 to assist said knocking over.

During that phase in the before-described stitch-forming operation when the locking thread loop *b* is cleared below the needle beard and passed through the old loop on to the exterior of said beard, (Figs. 6 and 7), the stitch thread appertaining to the old loop *a*, i. e., the sinker bars on each side of the stitch loop extend beneath the sinkers 4, 6, within an arcuate cut-out or recess 6a on the underside of the divider sinker 6 immediately at the rear of the neb 11, and if desired, but not necessarily, in an undercut recess 4a at the end of the jack sinker 4, the top of said recess or recesses being level or substantially level with the closed end of the forward sinker throat 10 accommodating the locking thread; and in this manner the needle can be raised with the old loop *a* in the subsidiary hook 3 thereof without exerting undue strain on said old loop or without unduly extending said loop.

In the production of an ordinary or normal knitted stitch the needle operation is similar to that when employing an ordinary bearded needle, that is to say a previously formed loop is cleared below the beard while the needle is raised, new stitch thread is fed into the beard, the needle is lowered, the beard pressed and the old loop knocked over.

It will, of course, be appreciated that as the movements which require to be imparted to the needles and sinkers when making a locked stitch are different from those to be imparted when making an ordinary stitch, the cams for effecting the needle and sinker movements when making a locked stitch are shaped different from the cams for effecting the movements when

making a normal stitch. To this end specially shaped locking stitch cams are provided for the needle and sinker operation, the necessary movements being transmitted from said cams through suitable pivoted lever devices carrying trucks or rollers which are maintained in engagement with the cams by springs. The arrangement is such that while locking stitches are being produced the needle and sinker cams appertaining to plain stitches are inoperative, and vice versa. Additionally, fashioning or transfer cams are provided adapted to be brought into operation when the stitch-forming cams are inoperative.

By way of example, the invention is illustrated as applied to a straight bar machine of the Cotton's patent type having a single head, such a machine being known in the trade as a Wildman machine. The drive is transmitted from main drive shaft 15 through intermeshing gears 16 to the main cam shaft 17 on which are fixed the several cams for effecting the requisite stitch-forming operations. On the cam shaft 17 is also fixed a gear wheel 18 meshing with a larger gear 19 carried by and rotating in unison with a draw bar cam 20 with which coacts a cam truck or roller 21 carried by a quadrant lever 22 pivoted at 23 and meshing at its upper end with a gear 24, said draw bar cam operating rotatably to reciprocate the draw bar in the manner customary in this type of machine to impart reciprocating movement to a number of endless thread carrier bands or like flexible members 25 for effecting the requisite traverse of the thread carriers along a row of needles carried by the needle bar 26. The thread carrier bands 25 operate on vertical axes and are closely disposed one behind the other at the front of the machine where the thread carriers are fixed to said bands, the rear portions of the bands 25 being spaced apart and having fixed thereon saddle members 27 by means of which the endless carrier members 25 are selectively traversed by the selective engagement therewith of catch elements 28 carried by a box or bracket 29 suitably fixed to an endless travelling band or chain 30 operating on horizontal axes. The endless chain 30 is traversed to and fro through suitable gear from the aforesaid draw bar quadrant 22 in the manner customary in this type of machine, and the selective displacement of the catch elements 28 for selecting the carrier band 25 to be traversed is also effected by the longitudinal movement of selector rods 31. Simultaneously with the movement of the selected thread carrier band 25, reciprocating movement is also imparted to the usual slur cock operating to impart the requisite projection to the sinkers, the slur cock movement being effected by rotation of the spiral 32, the upstanding thread on which coacts with the usual slur cock carrier.

As aforesaid, the production of locked or tied knitted stitches necessitates the employment of cams for producing ordinary or plain stitch loops and additional cams for producing stitch-locking loops, i. e., for locking or tying the plain loops, and the arrangement is advantageously such that the machine operates to produce courses of ordinary stitch loops alternating with courses of stitch-locking loops. To this end the cams on the main cam shaft 17 functioning in the known manner to operate and control the movement of the stitch-forming elements in the production of normal knitted stitches must have associated therewith other cams adapted to be brought into operation for producing the locked or tied

stitches, together with means for causing said cams selectively to function at the required times. The two closely disposed cams 33, 34 appertain to the operation of the catch bar 35 for effecting the requisite in and out motion of the sinkers, the cam 33 operating when making ordinary or plain stitches and the cam 34 when making locked stitches. Alongside these cams are the usual cam discs for imparting the requisite up and down motion to the catch bar 35 and also cams for operating during fashioning or stitch transference, that is to say when the stitch cams are inoperative. Two further cams are also advantageously provided closely alongside the aforesaid cams functioning in the normal manner for imparting motion to the knocking-over bits 14 both during stitch production and while fashioning. Motion is transmitted from the aforesaid catch bar cams 33, 34 through the intermediary of a cam truck 36 (Figs. 10 and 11) carried by a spring influenced lever 37 which extends to and is fixed to a rotatable catch bar shaft 38 extending along the machine, said shaft having also fixed thereto a number of upwardly extending links 39 pivoted at their upper ends to horizontal links or rods 40 which are in turn connected with the catch bar 35. By this means as the truck 36 rises and falls, the catch bar 38 is rocked and horizontal movement is imparted to the links or rods 40 to impart movement to the catch bar. The axle of the truck 36 is embraced by the forked end of a cranked arm 41 extending down at the rear of the machine and rotatably mounted on its lower end upon a shaft 43 which constitutes one 35 of a pair of horizontal cam selector shafts 42, 43 located respectively at the front and rear of the machine.

Two further closely disposed cams 44, 45 fixed to the cam shaft 17 function to impart the required vertical motions to the needles carried by the needle bar 26, the cam 44 functioning when making plain stitches and the cam 45 when making locked stitches. Adapted selectively to coact with these cams 44, 45 is a cam truck 46, the radial displacement of which is converted into vertical motion at the needles through the medium of a truck-carrying arm 47 fixed to a rock-shaft 48, one or more further arms 49 also fixed to said rock shaft 48 and rotatably upon a cross 50 spindle 50 to which spindle are suitably clamped the customary brackets 51 carrying the needle bar 26. Consequently it will be seen that an up-and-down motion is imparted to the cross spindle 50 carrying the needle bar brackets 51. The stub axle carrying the truck 46 has fixed thereto a pair of spaced collars 52 (Fig. 12) between which and around said axle is assembled the forked extremity of a truck displacing arm 53 (Fig. 11) rotatably mounted at its lower end 55 upon the aforesaid rear cam selector shaft 43.

Closely alongside the cams 44, 45 may be mounted cams for imparting motion to the before-mentioned thread carrier selector rods 31. The in and out motions of the needles, i. e. 65 needle pressing motions, are transmitted from two further closely disposed cams 54, 55, the cam 54 functioning when making ordinary stitches and the cam 55 when making locked stitches; and as is the customary practice the needle pressing 70 motions are effected simultaneously with the vertical motions of the needles. This is accomplished by mounting on the aforesaid rock shaft 48 a downwardly depending arm 56 carrying at its lower end on a laterally extending stub axle 75 a cam truck 57; a second downwardly depending

arm 58 being fixed to the aforesaid cross shaft 50 to which the needle bar brackets are secured, and the lower end of said arm 58 having pivoted therat a hand lever 59 having an adjustable hook connection to a pin on the truck-carrying 5 arm 56 (Fig. 11), thereby providing a parallelogrammic lever device. Embracing the stub axle of the cam truck 57 is the upper forked extremity of a truck-shifting arm 60 mounted at its lower end upon the front cam selector shaft 42.

10 Fixed on the cam shaft alongside the needle presser cams 54, 55 is a cam disc adapted to function during fashioning, i. e., when said presser cams are inoperative; whilst at the same position on the cam shaft may also be fixed the usual 15 cams for effecting the vertical motion of the transfer points during fashioning.

Further along the cam shaft is also fixed the customary quality cam 61 with which coacts a truck 62 carried at the upper end of a truck arm 63 mounted at its lower end upon a cross shaft 64, generally known as the regulating shaft. This shaft 64 which is capable of rotation has fixed thereon a sleeve 65 with upstanding plate 66 on which plate is pivoted a quadrant arm 67 extending over said plate 66 and coacting at its upper part with screwed studs 68 adjustably mounted within a part 69 constituting an extension of the aforesaid truck arm 56 appertaining to the needle presser cams 54, 55. The lower toothed end of 30 the quadrant arm 67 meshes with a rack 70 slideable within a slot in the aforesaid sleeve 65 on the shaft 64 so that by movement of said rack the upper end of the quadrant arm 67 is brought into register with selected of the screwed studs 35 68 which project from the part 69 to different degrees. During normal stitch production, i. e., when knitting ordinary or plain stitches, the quality of the stitch loops or the length of said loops drawn by the relative movement between 40 the needles and sinkers is effected from the pattern drum 71 (Figs. 10 and 12) through the intermediary of a lifter 12, pivoted bell crank 73 and horizontal bar 74 which is adjustably screwed at 45 75 to a slideable sleeve 76 mounted on the regulating shaft 64 and carrying the aforesaid rack bar 70. In order, however, to determine the quality of the stitch-locking loops during the production of locked or tied stitches, the quadrant arm 67 has imparted thereto an extended 50 pivotal motion to bring same into register with additional adjustable studs 77 (Fig. 12) carried by a lateral extension of the member 69 on which said studs are mounted, and this additional movement of the quadrant arm 67 is effected by axial 55 displacement of the front selector shaft 42 which has fixed thereon a forked bracket 78 carrying an adjustable stop 79 adapted, on displacement of the shaft 42, to pivot a short centrally pivoted arm 80 and by so doing longitudinally move the 60 bar 74 fixed to the sliding sleeve 76 and move the rack bar 70 for pivoting the quadrant arm 67 to the required extent. The before-mentioned holding down bar 12 is also operated and controlled from cams on the cam shaft 17. These 65 cams are shown at 81 and 82, 81 being the cam operating when producing plain stitches and 82 when producing locked stitches. An additional cam disc is also provided alongside, functioning during fashioning. Coacting with the cams 81, 70 82 is a truck 83 carried on a stub axle 84 at the lower end of an upwardly extending lever 85, which latter is at its upper end fixed to a rock shaft 86 carried at its ends in bearings 87 on the machine frame (Fig. 10). On this shaft 86 75

are fixed upstanding arms 88 carrying sleeves 89 (Fig. 15) within each of which is slidably assembled a spring influenced catch pin 90 having a bevelled nose 91. Normally the nose 91 of each pin 90 projects above the sleeve 89 to an extent sufficient to coat with the vertical end face of a bevelled stop 92 provided on the underside of a horizontal slidably mounted bar 93, the two bars 93 having suitably connected thereto the holding down bar 12. A spring 94 connected at one end to an element on the sliding bar 93 and at the other end to an element on the stationary guide 95 serves normally to hold the stops 92 in engagement with the projecting catch pins 91, and during the production of locked or tied stitches rocking motion is imparted to the shaft 86 pivotally to displace the arms 88 carrying the catch pins 91, and in so doing the holding down bar 12 has imparted thereto the requisite motions described earlier in the specification. When it is desired to withdraw the holding down bar 12 out of operation, the catch pins 91 are lowered against their springs out of engagement with the stops 92 by the pivotal movement of a small hand lever 96 which is pivotally connected to the lower end of the catch pin 91 and when swung downwardly withdraws said pin 91 and holds same out of operation, see Fig. 15.

The stub axle 84 of the cam truck 83 coaxing with the holding down bar cams 81, 82 is embraced between fixed collars by the forked end of a truck shifting arm 97 loosely carried on the regulating shaft 64, that part of the arm 97 encircling the shaft 64 being in turn embraced by the aforesaid forked bracket 78 fixed to the cam selector shaft 42.

From the foregoing description it will be appreciated that the truck shifting arms appertaining to the holding down bar 12 and, needle presser cams 54, 55 are capable of being displaced laterally for shifting the trucks from the cams appertaining to the plain or normal stitches to those appertaining to the locked stitches and vice versa by suitable operation of the front cam selector shaft 42, while the trucks appertaining to the catch bar cams 33, 34 and needle cams 44, 45 are adapted to be similarly displaced by operation of the rear cam selector shaft 43, and one method of automatically effecting this displacement of the several cam trucks will now be described.

As before-stated the machine is advantageously arranged to produce ordinary stitches on alternate courses and locked or tied stitches on the remaining alternate courses; in other words, when thread has been laid along the needle row in one direction a course of ordinary stitch loops is produced from said thread, and when the thread is returned along the needle row in an opposite direction the stitch loops produced on the last preceding course are locked or tied. To do this the two selector shafts 42, 43 are simultaneously moved first in one direction and then in the opposite direction to bring the plain stitch cams and the locking stitch cams into operation on alternate courses. While this type of fabric is being produced, a pivoted catch element 98 on the machine frame is maintained in the raised position indicated in full lines in Fig. 13, this being effected by causing a pivoted, spring influenced pattern drum follower 99 linked to the free end of said catch to traverse a circumferential row of closely disposed bits 115 on the pattern drum 71. With the catch 98 so raised, a to and fro motion is imparted to the selector shaft 42 by means

of suitable pivoted links 100 terminating at one end in a collar 101 provided on said selector shaft 42 and at the other end in a roller or truck 102 coaxing with a face cam 103 rotating in unison with the draw bar cam 20. The collar 101 coacts with a sleeve 104 encircling the shaft 42 between said collar 101 and a second collar 105, and the face cam 103 is so designed that for approximately one half of the revolution of said cam the shaft 42 is axially displaced against the influence of the spring 106, while for the remaining half of the revolution said spring returns the shaft 42 to its normal position. The movement imparted to the front selector shaft 42 is simultaneously conveyed to the rear selector shaft 43. In one method of accomplishing this the aforesaid sleeve 104 has secured to a depending portion thereon a short rod 107 connected at its free end beyond the machine frame to a boss 108 rotatably mounted at the one end of one link 109 of a pair of toggle links 109, 110 extending alongside of the machine, the end of the second toggle link 110 being similarly connected to the rear selector shaft 43. The two links 109, 110 are connected together at 111 by pin and slot connection and each link is itself pivoted midway between its extremities on pivots 112 carried by an angle bar or similar fixed member 113.

When the machine operates to fashion the fabric being produced thereon, i. e., when stitch transference is being effected by the customary transfer points, the stitch producing cams are rendered inoperative and the several cam trucks are brought into engagement with the usual transfer cams for effecting the requisite relative motion of the stitch-forming elements and transfer points. Also during stitch transference the draw bar mechanism for traversing the thread carriers and slur cocks is thrown out of operation, and this is effected by shogging the cam shaft 17 so as to declutch the draw bar mechanism and at the same time cause the cam trucks to move over on to the transfer or fashioning cams. The mechanism for accomplishing this is well known and, therefore, does not require to be described in detail. In view of the fact that the stitch transference occurs at the termination of the production of a course of ordinary stitches, that is to say at the time when the needles carry normal stitch loops prior to the locking of said loops, it will be understood that the clutching of the cam shaft to the draw bar operating mechanism must be effected when the selector shafts 42, 43 have been moved to a position to bring the several cam trucks in engagement with the locking stitch cams, as the next course of stitches to be formed are locking stitches. Consequently the re-clutching of the cam shaft to the draw bar mechanism is so timed that the cam trucks are brought into engagement with the locking stitch cams. The requisite shogging motion of the cam shaft is effected by any known or suitable means operated from a pattern chain 114, and the racking of this pattern chain and also the pattern drum 71 is also advantageously accomplished from the cam shaft through suitable clawker mechanism.

If at any time ordinary fabric is to be produced, that is to say fabric other than locked stitch fabric, the aforesaid catch member 98 associated with the selector shaft 42 is lowered to engage the collar 105 or other member on said shaft and maintain the truck 102 out of engagement with the draw cam 103, thereby rendering the several locked stitch cams on the cam shaft 75

17 inoperable for any predetermined length of time. The lowering of the catch 98 is effected by causing the pivoted spring influenced pattern drum follower 99 (Figs. 13 and 14) linked to the 5 end of the catch to move down out of engagement with the series of raised bits 115 on said drum. For example, this plain (unlocked) fabric may be produced when forming the welt of a stocking blank.

10 It is to be understood that all of the several cam trucks are pulled by suitable springs towards their respective cams, and each or any of the truck carrying arms may have associated therewith means for relieving the cams from the wedge 15 or pressure of the trucks during shogging. One such means is illustrated by way of example in Fig. 11 as applied to the truck associated with the cams effecting vertical movement of the needles, said means comprising a laterally projecting arm 20 116 carrying a pin 117 coaxing with a vertical slot 118 in a suitable bracket or member 119, the pin 117 reaching the lower end of the slot 118 on an adjusting screw and supporting the cam truck slightly clear of the cams during shogging.

25 In Figs. 17 to 20 inclusive the several cams employed in the production of locked stitch fabric are more clearly shown. In Fig. 17 the holding down bar cam 82 functioning when producing locked stitches is shown superimposed over 30 the cam 81 which functions when producing plain stitches, the latter being a circular disc. The cam truck 83 is shown bearing on the locking stitch cam at a position coinciding substantially with the position of the stitch-forming elements in Fig. 1, and between this position, indicated at A, and the position D which coincides with Fig. 4 the cam 82 functions first to move the holding down bar 12 quickly towards the needles, then to retard this movement and finally to move the bar quickly substantially close up 40 to the needles. Continued rotation of cam 82 quickly withdraws the bar 12 a small distance and then fully withdraws said bar to the knocking over position indicated at H which corresponds with Fig. 8.

45 In Fig. 18 is shown the locking stitch cam 45 for effecting vertical movement of the needles superimposed over the plain stitch cam 44, and the contour of the cam 45 from the position A to the position H is such as to effect the vertical movements imparted to the needles during the production of a locked stitch, the eight successive positions A to H at the periphery of the cam traversed by the truck 46 corresponding 50 with the eight successive positions of the needle illustrated in Figs. 1 to 8. Advantageously also the locked stitch cam 45 is provided at its periphery with a radially adjustable nose or bit 120 for finely adjusting the projection of the 55 needles at the position in Fig. 6 in accordance with the quality of the plain stitch loops on the needles.

60 In Fig. 19 is shown the locking stitch cam 55 for the in and out or pressing movement of the needles superimposed over the plain stitch cam 54 and also showing the quality cam 61 at the rear thereof. In this figure again the eight successive positions at the periphery of the cam 55 indicated from A to H correspond with the 65 positions shown in Figs. 1 to 8, that is to say the rotation of the cam 55 from A to H effects the pressing movements of the needles from the feed of the locked stitch thread to the knocking over of the stitch locking loop to produce a 70 locked stitch, the quality cam 61 simultaneously 75

co-operating with the cam 55 to produce locking stitches of the requisite size or quality.

75 In Fig. 20 is shown the locked stitch cam 34 over the plain stitch cam 35 for governing the in and out motion imparted to the catch bar controlling the sinkers, it being understood that said cam functions in unison with the customary cam appertaining to the up and down motion of the catch bar. Here again the peripheral contour of the cam 34 from the position A to 10 the position H controls the catch bar during the production of locked stitches throughout the steps illustrated in Figs. 1 to 8, the eight positions A to H coinciding with the eight positions in said Figs. 1 to 8. The jack sinkers 4 are, of course, projected between the needles by the usual slur cock device, the cam 34 operating to project the divider sinkers 6 and withdraw both the jacks and dividers. On this catch bar cam 34 is also provided a radially adjustable nose or 20 bit 121 which functions to ensure that the locking loop is drawn tightly up on to the needle shank at the positions illustrated in Figs. 5 and 6 irrespective of the quality of said locking loop. The several cams associated with the before-25 described locking stitch cams are designed to function in the customary manner for producing plain or unlocked stitches and, therefore, need no description.

30 In the production of a selvedged knitted blank or article wherein courses of ordinary stitch loops are produced alternating with courses of locking loops, although there is no difficulty in producing an effective selvedge at that edge of the fabric where the thread carrier is reversed to 35 produce a course of locking stitches, the production of a satisfactory selvedge at the opposite edge is not so simple. The main reason for this is that although at the one edge of the fabric the thread is without difficulty controlled by the 40 sinkers to produce a course of plain stitches prior to the traverse of the carrier being reversed, at the opposite edge of the fabric, i. e. at the termination of the locking thread draw, the angle at which the thread extends up to the 45 thread guide or carrier coupled with the peculiar motions hereinbefore described for producing locked stitches on the specially formed needles render it impossible, without special provision, to produce a stitch on the end needle, 50 i. e. the selvedge needle. The present invention, therefore, includes means whereby, subsequent to the termination of the draw or traverse of the locking thread, the thread carrier is shogged a further short distance to the extent of one or 55 more needles so as to permit of said thread being brought under control and enable an effective selvedge to be produced. In one method of accomplishing this on the class of machine under consideration, a racking device is provided at the 60 end of the machine functioning to effect this short additional motion of the thread carrier, said racking device also having associated therewith means for selvedging during the production of fashioned fabric, i. e., during stitch transference.

65 As aforesaid the saddle members 27 have associated therewith the thread carriers, the traverse being effected by the engagement of a catch element 28 with a saddle 27, and the extent of traverse is determined by a stop 122 carried by a stop bracket 123 threaded upon a right and left hand screw threaded spindle 124; two of said brackets 123 with stops 122 being provided, one at each 70 end of the machine, one on the right hand 75

threaded portion of the spindle 124 and the other on the left hand threaded portion thereof. Thus by rotation of spindle 124 in the known manner stops 122 are adjusted. On the stop bracket 123 is pivoted a catch arm 125 (Fig. 23) advantageously normally pulled down by spring 126, a depending trip arm 127, being pivotally connected to said catch and held by spring 128 against an adjustable stop 129 on said catch. The depending tripping arm 127 is pivotally displaceable from the vertical position away from the catch 125 but is prevented from moving beyond the vertical in the opposite direction without lifting the catch. When the carrier reaches the normal end of its traverse, an upstanding lug 130 on the carrier saddle 27 passes beneath the bevelled end of the catch 125 so as to become located between said catch and the stop 122, and a further rotary movement imparted to the screwed spindle 124 then causes the saddle with carrier to be traversed a further short distance to carry the thread over one or more additional needles beyond the normal selvedge needle. On the reverse or return motion of the catch bracket 29 to effect the return motion of the carrier, said bracket coacts with the depending trip arm 127 to lift the catch 125 clear of the upstanding lug 130 on the saddle, after which the stop bracket 123 is adjusted back again for the next course.

The extra rotary movement of the oppositely screwed stop spindle 124 for imparting to the carrier a short additional traversing motion at the termination of the locking thread draw is advantageously effected from suitable cams on the cam shaft 17 as hereinafter described.

One end of the aforesaid oppositely screwed stop spindle 124 has suitably geared thereto a stub shaft 131 on which are fixed two oppositely toothed rack wheels 132, 133, and over said wheels are pivoted two oppositely extending clawker arms 134, 135 pulled down by springs 136 and connected or constructed for simultaneous pivotal displacement, the clawker 134 being adapted to coact with the one rack wheel 132, and the clawker 135 with the rack wheel 133. The operation of the clawkers to effect rotation of either of the rack wheels 132 or 133 and rotate the stop spindle 124 in one direction or the other is advantageously effected by imparting rocking motion to a bell crank lever 137 connected by an adjustable link 138 to one arm of a bell crank lever 139 pivoted on a fixed spindle 140, the opposite arm of said bell crank lever carrying a truck 141 bearing on the peripheries of two closely disposed racking cams 142, 143 on the cam shaft 17. Operating between the two rack wheels 132, 133 is a bluff wheel 144 (Fig. 22) for bluffing the clawkers 134 and 135 clear of said rack wheels, said bluff wheel being rotatable independently of said rack wheels and having at two positions in its periphery V-shaped notches 145 (Fig. 21) which when either of same is brought into register with a clawker, permits said clawker to engage with a rack wheel and impart rotation thereto. The bluff wheel 144 is advantageously rotated through an adjustable link 146 pivotally connected to the one arm of a bell crank lever 147 mounted on the aforesaid shaft 140, the other arm of said bell crank lever carrying a cam truck 148 bearing on two closely disposed bluffing cams 149 and 150 on the cam shaft 17.

In Fig. 24 is shown a face view of the several cams on the cam shaft 17 for controlling the

racking and bluffing cam which function when producing parallel (unfashioned) fabric, and Fig. 26 showing the racking and bluffing cams functioning when producing fashioned fabric. During the production of parallel sided fabric, at the termination of the draw or feed of the locking thread, a rise 149a on the bluff cam 149 effects rotation of the bluff wheel 144 to bring one of the V-shaped recesses 145 into such a position that at the rise 142a on the rack cam 142 one of the clawkers 134, 135 is brought into engagement with one of the rack wheels 132, 133 and effects partial rotation thereof, thereby imparting further rotation to the screw-threaded stop spindle 124 and giving a short further shogging motion to the thread carrier to the extent of one or more needles. At the commencement of the return motion of the thread carrier a fall 149b on the bluff cam 149 again partially rotates the bluff wheel 144 in an opposite direction to bring the other clawker into engagement with the second rack wheel which has oppositely directed teeth, and a fall 142b on the rack cam 142 then imparts rocking motion to said clawker to rotate the last named rack wheel and thereby impart opposite rotation to the stop spindle 124 to an extent sufficient to return the previously shogged thread carrier stop back over the one or more extra needles. Subsequently at the position 149c the clawkers are raised by rotation of the bluff wheel clear of the two rack wheels and the thread draw takes place in the normal manner. The before-described operations continue at the end of each thread draw during the production of parallel sided fabric, it being understood, however, that although the additional motion is imparted to the stop spindle 124 at the end of each draw, the thread carrier is itself only traversed the extra one or more needles at the end of alternate thread draws, i. e. at the termination of each locking thread draw.

When it is required to produce fashioned fabric, that is to produce narrowed fabric by stitch transference, the cam shaft 17 has imparted thereto a short shogging motion as before mentioned, and in doing this the cam truck 148 is moved from one bluff cam 149 to the closely disposed bluff cam 150, while the other cam truck 141 is moved from the rack cam 142 to the closely disposed rack cam 143 appertaining to the fashioning. This shogging from one cam to the other takes place at the end of the plain or normal stitch thread draw immediately after the extra rotary motion has been imparted to the stop spindle 124 to shog the stop bracket 123 outwards. When the racking and bluff cams have been shogged relatively to their trucks a fall 150a on the bluff cam 150 partly rotates the bluff wheel 144 so as to enable a clawker to be operated by a fall 143a on the rack cam 143 again to rotate the stop spindle 124 in an opposite direction and return the stop bracket 123 to its normal position. Stitch transference or fashioning then takes place and the bluff wheel 144 is again operated by rise 150b to permit of a further outward racking of the stop carrier 123 by the rise 143b on the racking cam 143; and when the trucks again reach the position 151 shogging of the cam shaft 17 is again effected to bring the trucks 141 and 148 into engagement with the cams 149 and 150. The shogging from parallel work to fashioning may be effected at predetermined intervals.

In order to facilitate selvedging and obviate the possibility of thread breakage a plurality of

specially shaped divider sinkers may be employed at each selvedge, said divider sinkers having an extra elongated throat 152 (Fig. 29) extending parallel with the under edge of the sinker and substantially near said edge for accommodating the thread loops.

We claim:

1. In a knitting machine for producing fabric in which a loop of a locking thread is passed through and also around a previously formed stitch loop, the combination with loop forming knitting needles, thread-feeding means therefor and means to operate said needles to receive thread from the said feeder and produce therefrom ordinary stitch loops, of other means functioning subsequently to the production of the ordinary stitch loops and operating to receive a locking thread and form loops therefrom and pass said loops through and around said stitch loops to lock them, and fabric-holding means functioning to restrain the stitch loop on the knitting needle from movement in both directions lengthwise of said needles so that locking loops can be passed through said stitch loops.
2. In a knitting machine according to claim 1, the employment of needles each having the end of its hook turned back upon itself to form a subsidiary hook, means operating the needle longitudinally to engage a ground loop in the subsidiary hook and lift it over a locking loop, and means for holding the fabric down during this operation.
3. In a knitting machine for producing fabric in which a loop of locking thread is passed through and also around a previously formed stitch loop, loop-forming knitting needles, elements movable with the needles cooperating with other elements movable relative to the needles to pass one loop through or over another and means operating to engage the fabric adjacent to the needles and restrain it from movement longitudinally of the needles so as to hold the stitch loops in a position on the needles for permitting the locking loops to be passed therethrough.
4. A knitting machine according to claim 3 and including a fabric holding-down bar at the plain side of the needles.
5. A straight bar knitting machine embodying spring or bearded needles, each or selected of which has the tail end of its beard turned back towards its shank to form a comparatively small subsidiary hook constituting a loop-manipulating element, thread-feeding means, means operating said needles to receive thread and produce therefrom ordinary stitch loops and other means functioning subsequently to the production of said ordinary stitch loops to operate the needles to clear the stitch loop below the needle beard, sink a loop of locking thread on the needle above said stitch loop, cause said stitch loop to become engaged by the subsidiary hook of the beard, pass the locking thread loop through said stitch loop while engaged by said subsidiary hook and cast off the locking loop over said stitch loop, and means operating to maintain the locking thread loop clear of the stitch loop while the latter is brought into engagement with the subsidiary hook of the beard and to hold the fabric down while the locking loop is passed through the stitch loop on to the exterior of the said beard prior to knocking over.
6. A method of producing knitted fabric upon a knitting machine by the employment of spring or bearded needles wherein a locking loop is passed through and also around a previously

formed stitch loop, and wherein the stitch loop and locking loop are received in the needle beard, and said loops are separated and controlled in their movement lengthwise of the needle while both are within said beard to enable the locking loop to be passed through the stitch loop.

7. In a straight bar knitting machine embodying spring or bearded needles each having the tail end of its beard turned back to form a comparatively small subsidiary hook, thread feeding means, means operating said needles to receive thread and produce therefrom ordinary stitch loops and means operating to produce stitch locking loops and to lock or tie stitches therewith, said last-named means functioning to clear said stitch loops on to the needle shanks, feed stitch locking thread into the beards, retract said needles to carry the locking thread to the top of the beards and also to carry the stitch loops into the beards above the subsidiary hooks, to cause the said stitch loops to be caught by the subsidiary hooks, to clear the locking thread loops below the beards while the old stitch loops are still held in said subsidiary hooks, to draw the locking loops through the old loops and finally to cast the locking loops off the needles around the old loops which are still retained on the needles, and means operating during the production of a locked or tied stitch to ensure that the locking loop is maintained clear of the stitch loop to be locked while the latter is being engaged by the subsidiary hook of a needle beard, and to hold down already formed fabric on the needles so as to permit a stitch locking loop to be passed through a stitch loop on to the exterior of the needle beard prior to knocking over.

8. In a straight bar knitting machine, spring or bearded needles each having the tail end of its beard turned back to form a small subsidiary hook, means operating to produce on said needles ordinary knitted stitches, means operating to produce on the same needles locked or tied stitches, said last named means functioning to cause stitch locking thread to be received in the beard of each needle, sink a loop from said thread on the needles, anchor the stitch loop to be locked in the subsidiary hook of the beard, pass the locking thread loop through said anchored stitch loop and finally cast off said locking loop over and around the stitch loop which is still retained in the needle beard, a movable bar or strip co-operating with thread controlling sinkers, means for projecting said bar towards the needles between the stitch loops and locking loops thereon, means for causing said bar to hold down the already produced fabric while the locking loops are being passed through the stitch loops on to the exterior of the needle beards and means operating subsequently to withdraw said bar from the needles.

9. A straight bar knitting machine according to claim 8 wherein the requisite movement of the holding down bar towards the needles is effected and timed by one or more rotary cams through the intermediary of link and lever mechanism and wherein the movement of said bar away from the needles is effected by spring means.

10. A straight bar knitting machine employing bearded needles each having the tail of its beard turned back to form a small subsidiary hook, thread feeding means, means operating to produce on said needles ordinary stitches, means operating to produce on the same needles locked or tied knitted stitches by causing loops of stitch

locking thread to be passed through and also around the stitch loops, jack sinkers operating between alternate needles to sink thread loops thereon, divider sinkers operating between the

5 remaining alternate needles subsequently to divide the sunk thread loops, said divider sinkers having two thread-accommodating throats located one below the other and the lower throat being located at the forward part of a nose portion 10 projecting in front of the upper throat, means operating during the production of a locked or tied stitch to cause stitch locking thread to be first received in the upper throat of a divider sinker and subsequently to pass into the 15 lower forward throat thereof and to be retained in and controlled by said forward throat throughout the major part of the locking stitch forming operation.

11. A straight bar knitting machine according to claim 10 including a movable bar or strip displaceable to and from the needles, and means whereby said bar is moved to the needles between the stitch locking loops and the stitch loops to be locked at the time said stitch locking 25 loops are brought into engagement with the forwardly disposed lower throats of the divider sinkers, said bar being maintained in this position while the needles are projected and the needle beards pressed to receive the stitch loops 30 in the subsidiary hooks thereof, and said bar also functioning to hold down the already produced fabric while the stitch locking loops are cleared below said needle beards prior to being passed through the old stitch loops and cast off the 35 needles around said loops.

12. A straight bar knitting machine according to claim 10 wherein the additional forward throat of each divider sinker has its rear or closed end level or approximately level with the under face or edge of that part of the sinker immediately at the rear of said throat.

13. A straight bar knitting machine according to claim 10 wherein the under edge of each divider sinker immediately at the rear of the forward throat thereof is formed with an arcuate recess, said recess functioning to obviate undue strain on a stitch loop during the passage of a locking loop therethrough when forming a locked or tied stitch.

14. A straight bar knitting machine according to claim 7 embodying cams for controlling the stitch producing mechanism for making plain or ordinary stitches, differently designed cams for controlling the stitch producing mechanism for making locked or tied stitches and means for automatically selecting said cams for operation at predetermined intervals.

15. A straight bar knitting machine according to claim 7 embodying cams for controlling the stitch producing mechanism for making plain or ordinary stitches, differently designed cams for controlling the stitch producing mechanism for making locked or tied stitches and means for automatically bringing the ordinary stitch cams into operation on alternate courses and the locking stitch cams into operation at the remaining alternate courses.

16. A straight bar knitting machine according to claim 7 embodying cams for controlling the stitch producing mechanism for making plain or ordinary stitches, differently designed cams for controlling the stitch producing mechanism for making locked or tied stitches and means for automatically selecting said cams for operation at predetermined intervals, e. g. on alternate

courses, said last named means comprising a cam associated with and moving in unison with draw bar mechanism one or more reciprocating shafts or spindles, arms connected with said shaft or shafts and cam trucks carried by said arms and bearing on the several cams from which movement is imparted to the stitch producing mechanism, the longitudinal displacement of the selector shafts functioning to shog the cam trucks from the ordinary stitch cams to the locking stitch cams and vice versa.

17. A straight bar knitting machine according to claim 8 including two rotary cams appertaining to a catch bar for sinker control, one operating during the production of ordinary 15 stitches and the other during the production of locked or tied stitches, two cams for controlling the vertical needle motions one functioning when making ordinary stitches and the other when making locked stitches, two cams controlling the 20 in and out or pressing motions of the needles one functioning when making ordinary stitches and the other when making locked stitches, two cams for controlling the holding down bar one imparting movement to said bar when producing 25 locked stitches and the second functioning to maintain said bar inoperative when producing ordinary stitches and means for selectively bringing into operation the several ordinary stitch cams and the several locked stitch cams at pre-determined intervals, e. g., at alternate courses.

18. A straight bar knitting machine according to claim 8, including two rotary cams appertaining to a catch bar for sinker control, one operating during the production of ordinary 35 stitches and the other during the production of locked or tied stitches, two cams for controlling the vertical needle motions one functioning when making ordinary stitches and the other when making locked stitches, two cams controlling the 40 in and out or pressing motions of the needles one functioning when making ordinary stitches and the other when making locked stitches, two cams for controlling the holding down bar one imparting movement to said bar when producing 45 locked stitches and the second functioning to maintain said bar inoperative when producing ordinary stitches and means for selectively bringing into operation the several ordinary stitch cams and the several locked stitch cams at pre-determined intervals, e. g., at alternate courses, 50 in which machine predetermined of the locked stitch cams are provided with regularly adjustable noses or bits for adjusting the size of the locking stitch loops.

19. A straight bar knitting machine according to claim 8 including two rotary cams appertaining to a catch bar for sinker control, one operating during the production of ordinary 60 stitches and the other during the production of locked or tied stitches, two cams for controlling the vertical needle motions one functioning when making ordinary stitches and the other when making locked stitches, two cams controlling the 65 in and out or pressing motions of the needles one functioning when making ordinary stitches and the other when making locked stitches, two cams for controlling the holding down bar one imparting movement to said bar when producing locked stitches and the second functioning 70 to maintain said bar inoperative when producing ordinary stitches and means for selectively bringing into operation the several ordinary stitch cams and the several locked stitch cams at predetermined intervals, e. g., at alternate 75

courses, combined with means for varying at will the size or quality of the stitches, and means for automatically controlling said variation during the operation of the machine.

5 20. A straight bar knitting machine employing bearded needles each having its beard turned back to form a comparatively small subsidiary hook, thread feeding means, cams for controlling mechanism operating to produce plain or ordinary stitches on the needles, differently designed cams for controlling mechanism operating to produce locked or tied stitches, a displaceable fabric holding down bar, cam means for controlling the operation of said bar during the production of locked stitches, means for holding said bar out of operation during the production of ordinary stitch loops, selector mechanism functioning to bring into operation the ordinary stitch forming cams at predetermined times and to bring into operation the locking stitch forming cams at other predetermined times, and means operating automatically at predetermined intervals to render inoperative the ordinary stitch and locking stitch producing mechanism and simultaneously to bring into operation fashioning or stitch transferring mechanism.

21. A straight bar knitting machine according to claim 20 and including a releasable locking catch device controlled from a rotary or travelling pattern drum or member and functioning to render operative and inoperative the cam selector mechanism so as to permit of the production of fabric embodying locked or tied stitches or fabric devoid of said stitches.

22. A machine according to claim 20 and including means whereby, at the termination of each course of stitch locking loops, the traverse of the thread forming said loops is extended over one or more additional needles beyond the normal selvedge needle so as to produce on said additional needle or needles a selvedge wale or wales.

23. A process of producing knitted fabric on a straight bar knitting machine employing bearded needles having the tails of the beards turned back to form small subsidiary hooks, said process consisting in making on successive courses normal knitted stitch loops and stitch locking loops for locking or tying said normal stitch loops, and the locking or tying of the stitch loops being effected by the following sequential operations, namely:—clearing the stitch loop to be locked below the needle beard, feeding

stitch locking thread to the needles above said stitch loop, sinking a loop of said locking thread on the needle, carrying the locking thread loop and stitch loop up into the needle beard, entering a bar member between the locking loop and 5 stitch loop to maintain same separate, pressing the needle beard, entering the stitch loop into the subsidiary hook on the beard, clearing the locking loop below the beard while the stitch loop is anchored in the subsidiary hook, operating 10 the aforesaid loop spacing bar so as to hold down the previously formed fabric, again pressing the needle beard and passing the locking loop through the stitch loop and on to the exterior of the beard and finally casting off the locking loop over and 15 around the stitch loop which is still retained on the needle.

24. A straight bar knitting machine equipped with bearded needles each having its beard turned back to form a comparatively small subsidiary hook, thread-feeding means, means for producing ordinary stitches and locking stitches on the said needles, a displaceable fabric-holding-down bar, means for controlling the operation of said bar during the production of locking 25 stitches, means for holding said bar out of operation during the production of ordinary stitches, fashioning or stitch transferring mechanism, means operating automatically at predetermined 30 times to render inoperative the means for producing ordinary and locking stitches and to bring into operation said fashioning or stitch transferring mechanism, and means whereby, at the termination of each course of locking loops, the traverse of the thread forming said loops is ex- 35 tended over at least one additional needle beyond the normal selvedge needle so as to produce on said additional needle or needles a selvedge wale or wales, which said means includes a rack device for imparting a short shogging motion in 40 opposite directions to thread carrier traversing means, clawker mechanism co-operating with said rack device, a rotary cam device functioning to operate said rack device through said clawker mechanism to impart the requisite shogging motion to the thread carrier at the required times, bluffing means for the clawker mechanism and a further rotary cam device for controlling said 45 bluffing means and for rendering operative and inoperative the rack device.
